UNITED STATES PATENT OFFICE.

CHARLES E. EMERY, OF BROOKLYN, NEW YORK.

WORKING-BEAM FOR STEAM-ENGINES.

SPECIFICATION forming part of Letters Patent No. 398,956, dated March 5, 1889.

Application filed June 7, 1888. Serial No. 276,387. (No model.)

To all whom it may concern:

Be it known that I, CHARLES E. EMERY, a citizen of the United States, residing in Brooklyn, county of Kings, and State of New York, (office New York city,) have invented certain new and useful Improvements in the Working-Beams of Steam-Engines; and I do hereby declare that the following is a full, clear, and exact description of the same, reference being had to the accompanying drawings, making part of this specification.

The beam of the typical American beam-engine is constructed with a heavy lozenge-shaped strap of wrought-iron, into which is keyed a cast-iron web in the general form of a cross, with horizontal arms longer than the vertical ones. At the longer angles of the lozenge pin-holes are provided for the main connections. The web of the beam is provided with a central opening for the main center pin and other openings each side of the same for connections to pumps, &c. The beam-strap is ordinarily a large forging, "built up," as it is called, by welding together many pieces. A forging of this kind is deficient in strength, homogeneity, and extensibility as compared with smaller bars of rolled iron. Such beam-straps have broken in many cases, causing the wreck of the principal parts of the engine and much of the surrounding wood-work, and also not unfrequently loss of life. In my improved beam the beam-strap is composed of a number of eye-bars similar to those used in the construction of bridges, which are articulated together and secured in tension over the web of the beam. The art of making eye-bars has reached a high state of perfection. The shanks are in such form that they can be worked so as to secure the highest possible tensile strength of the material, and by well-known processes and proportions the eyes can be made of the same strength as the bars. The eye-bars can therefore be made much stronger per unit of section than the heavy forgings previously used. A defect in one will rarely cause breakage of the whole, and if the number of bars and factor of safety be made sufficiently large one bar may break and the others continue to do the work until the difficulty is discovered and remedied.

In the drawings, Figure 1 is a vertical elevation of one form of the working-beam as

improved, and Fig. 2 is a plan view of the strap of the same for a portion of its length. Fig. 3 is a part-length elevation of a modified form of the improved working-beam, and Fig. 4 is a horizontal part-length view of the strap for the same. Fig. 5 is a part-length elevation of another modification of the improved working-beam, and Fig. 6 is a part-length plan of the same. Fig. 7 is a view in elevation of one end of still another modification of the working-beam, and Fig. 8 a plan view of the same. Fig. 9 is an elevation of one end of still another modification, and Fig. 10 represents a split pin for the same. Fig. 11 is an elevation of a special saddle for the end of the web of the beam, and Fig. 12 is a plan view of the same. Fig. 13 is a side elevation of a special saddle for the ends of the short arms of the web of the beam, and Fig. 14 a plan view of a saddle for the ends of the long arms of the web of the beam.

A is the web of the beam, provided with long arms A' A', shorter arms, A² A², and diagonal arms A³ A³.

B B' b b' is the beam-strap, composed of a number of eye-bars.

Parts lettered C' represent plain clamps, C² plate-clamps with draw-key, and C⁴ bolt-clamps.

D is the main center.

E represents the main connection-pins at ends of beam; H, the pins for connecting the eye-bars together at the half-length of the beam.

F shows location for pins to connect to pumps, &c.

G are keys for tightening the compound strap over the web.

In all cases it is proposed to make the web A of the beam of the same general shape as now used with ordinary beam-straps. In Figs. 1 and 2 the four sides of the beam-strap are made up of eye-bars each of a length to form a side of the rhomboidal figure. The several bars are joined together at the ends by large pins E and at the top and bottom by large pins H. The pins E may be extended laterally and constructed with journals M for the main connections. The eye-bars on each of the sides of the rhomboidal figure are preferably arranged on the pins in pairs, the outer ones to the right and the in-

ner ones to the left, as in Fig. 2, or vice versa, and this arrangement is duplicated as many times as is necessary to secure the strength, four pairs being shown in Fig. 2. In some cases, however, an odd number of heavier bars may be arranged on one side and an even number of lighter ones with the same aggregate thickness on the other, as is common in bridge construction. The bars below the center engage at their ends with those above in the same general way—that is, they are arranged in pairs—the outer ones up and the inner ones down at one end of the beam, and the inner ones up and the outer ones down at the other.

In the construction shown in Figs. 1 and 2 the several pairs of straps are separated at the end by strut-plates J J J on the end of the web of the beam, (see Fig. 14,) which have eyes horizontally through them to receive the end pins, E, and may have vertical slots in their ends to receive keys j j j to engage with nicks in the pins E. Upon the ends of the shorter arms, A², are placed saddles K, which receive strut-plates k k k, (see Fig. 13,) which go between the pairs of eye-bars in the same way as described with relation to Fig. 14. The saddles K are set out from the ends of the shorter arms, A², by keys, as shown, and thereby tighten the strap upon the web of the beam. The strut-plates J J J, Fig. 14, may also be formed upon saddles, as is shown in Fig. 5, making adjustment at each of the angles, if desired. In Figs. 5 and 6 eyes are provided only at the ends of the beam, and the eye-bars are bent, as shown, over the two side arms of the web and preferably thickened at the bends to keep up the strength.

The saddles K' are fitted to the interior curves of the bars, and are set out by keys G' G' between the saddles and tablets on the ends of the short arms A² A² of the beam. The saddles may, however, be omitted and the ends of the beam carried out nearly to fit the strap and the keys applied directly between the ends of the arms and the bars forming the strap, if desired. The bars may be grouped in pairs and separated at each end by strut-pieces similar to those shown in Fig. 14, or the arrangement shown in Fig. 6 be used, in which there are practically two beams, each provided with a web and an eye-bar up and another down, or multiples of the same on each side of the same, the two beams being placed side by side and connected together at the center and as often as desired; also by the pins E E at the ends of the beam and those at F for the pumps. The two webs can be cast or constructed separately and bolted together, as shown in Fig. 6. When bolted together, the pins may be shouldered down at each end to pass through the beams. If cast together, the end pins should pass through sleeve-struts or distance-pieces. In either way it is possible to make the journals for the connections between the two parts of the double beam and on the center line of the

compound beam. Half of this beam will also be practicable with overhanging pins.

In the modification shown in Fig. 3 the eye-bars are articulated together only at the middle of the beam, and are bent round the end of the web; as is shown. Preferably the bars are brought close together at the ends and spread at the center to permit the articulation of an odd number on one side and an even number on the other. The strap is tightened by keys under side saddles, K, and by driving wedges G between the strap and end of the web.

To avoid running strut-plates J J between the pairs of eye-bars, as shown in Figs. 1, 2, and 14, it is proposed in certain cases to make end saddles, as shown in Figs. 11 and 12, which, as will be seen, are provided first with a wedge-shaped piece to wedge between the eye-bars, and in addition with a series of rudimentary strut-pieces, m n, one, m, turning down to rest under an eye-bar running up, the other, n, turning up to rest upon another eye-bar running down. The rear of this saddle is provided with means for wedging the same against the web, as in other cases.

Still another method of dispensing with the strut-plates shown in Fig. 14 is to form the bars at the ends with the projection P at right angles to the center line of the beam, as shown in Fig. 9, such projection for the upper bars, B, turning downward and for the lower bars, b, turning upward. The offset thus formed abuts against a wedge-shaped block, Q, which may be set out by wedges G from the end of the web of the beam, and thus tighten the bars on the web. These eye-bars are shown bent over the intermediate arms, as in Fig. 5, but evidently there may be side articulations, as well as end ones, as in Fig. 1. The offsets P may seem to be an insecure way of taking up the thrust; but the system will be theoretically correct so long as the lines passing through the centers of the upper and lower bars, B and b, and the center of the web intersect at the center of the pin E. To remove the look of insecurity, however, and stiffen the beam against the various wringing changes to which it may at times be subjected, it is proposed, as shown in Fig. 7, to make the end of the saddle-piece Q concave and to bore in it and in the abutting-face of the part P a hole, in which is to be inserted a large pin, R, thereby interlocking the saddle Q on the end of the beam and the projecting piece P on each of the bars firmly together, so the bars may be placed close together alternately up and down, as shown in Fig. 4, thus saving the room required for the strut-bars in Fig. 14. The pin R is also a convenient way of forming the thrust-connection at any angle, even if the web be not articulated at such angle, since the hole for the same may be bored in place after all the parts are clamped together and a large amount of hand-work saved. The lips p p on saddle Q may also be run out al-

ternately up and down between the eye-bars to engage with the horizontal portions of the lugs P and still further aid in steadyng and giving apparent stability to the structure, 5 and this construction may be adopted and the pin R omitted, or vice versa, if desired. Evidently, also, the saddle Q may be formed on the web and wedges placed in proper seats arranged opposite each other in the end of 10 the web and the projections P. In Figs. 7 and 9 the end pins may, if desired, be extended to form bearings for the main connections, or the saddle Q, as shown in Fig. 9, may have an opening, E, to receive the pin for the end 15 connections, and the pin S at the extreme end of the beam be used simply to articulate the joints, in which case it is preferable to divide it longitudinally and place wedges between the parts, as shown in Fig. 10, to insure 20 a solid fit calculated to resist both compressive and tensile strains. The bars may in these several ways be connected to form a continuous beam-strap, which can be tightened over the web in one of the ways shown 25 to act efficiently in tension; but in compression the full strength of the bars cannot be utilized unless they are prevented from buckling. This is accomplished by binding them together by means of clamps of different forms adapted to the portion of the compound strap operated upon, the spaces between the flat sides of the eye-bars opposite the clamps being previously filled with distance-pieces or chocks, so that the clamps will 30 bring all the bars laterally to a solid bearing. At the quarter-lengths of the beam the diagonal arms are fitted or wedged against the compound strap, and plate-clamps C³ C³, with holes for two or more bolts and for key, are clamped 35 by the bolts to the compound strap at the same time that the keys are driven, and thus prevent shake. To accomplish this the inner bolts adjoining the keys are made loose in the holes in the web, so that the key draws the 40 outer bolts tightly against the strap. The same arrangement or an ordinary band or plate-strap may be used at the half-lengths of the beam-strap when the eye-bars are not articulated at such points. At points where 45 the strap is clear of the web plain clamps C' C' are employed, consisting of two plates on opposite sides of the compound beam-strap held tightly together by bolts. U-bolts may also be used with a single outside plate to accomplish the same purpose. When the several bars are separated, as in Fig. 2, distance- 50

pieces s, with a thickness equal to the exact distance between the bars, are to be put between the latter and shaped substantially like the outside clamps, so as to receive the bolts and thus be kept in place. 60

If desired, the strap may be swelled out to correspond to the shape of the clamps and the bolts put through the lugs thus formed. 65

Bolts forming bolt-clamps C⁴ C⁴ may be put through the beam-strap to clamp the parts together, if desired, the metal of the bars being swelled out opposite the holes to keep up the strength. The distance-pieces between the bars are designated s, and are shown only at 70 the left in Fig. 2 over bolt-clamp C⁴ and for plate-clamps C³ and C' in Fig. 4, being omitted elsewhere to avoid confusing the drawings. The eyes of the bars are tightly clamped together, preferably by large nuts N, screwed 75 upon threaded portions of pins E and H.

What I claim as my invention, and desire to secure by Letters Patent, is—

1. In combination, to form a working-beam, eye-bars, connecting-pins, a web, and devices 80 for straining the eye-bars over the web.

2. In combination with a beam-strap composed of eye-bars and a web over which the eye-bars are strained, pins connecting the eye-bars provided with journals for the main connections. 85

3. A working-beam provided with a strap composed of eye-bars, a web over which the eye-bars are strained, and clamps and necessary distance-pieces applied at various intermediate points along the eye-bars to hold the same rigidly together, so that they will act as a unit in compression, substantially as described. 90

4. In a working-beam provided with a strap 95 composed of eye-bars and a suitable web, adjustable saddles transmitting the thrust of the eye-bars to the arms of the web.

5. In a working-beam, an eye-bar forming part of the strap and provided with a lateral 100 lug, P, near the eye, adapted to transmit the strains arising from the tension of the bar when connected with other parts to an arm on the web, substantially as described.

6. The web of a working-beam and a strap 105 for the same provided with a lateral projection at one of the angles, combined with a pin, R, substantially as described.
